UNITED STATES PATENT OFFICE

109,150

DESIGN FOR A SEWING MACHINE CABINET

Malcolm S. Park, Mount Kisco, N. Y., assignor to
The Singer Manufacturing Company, Elizabeth, N. J., a corporation of New Jersey

Application February 12, 1938, Serial No. 75,099

Term of patent 14 years

To all whom it may concern:

Be it known, that I, Malcolm S. Park, a citizen of the United States, residing at Mount Kisco, New York, have invented a new, original, and ornamental Design for a Sewing Machine Cabinet, of which the following is a specification, reference being had to the accompanying drawing, forming a part thereof.

Figs. 1 and 2 are perspective views of a sewing machine cabinet showing my new design.

I claim:

The ornamental design for a sewing machine cabinet, as shown.

MALCOLM S. PARK.
